UNITED STATES PATENT OFFICE.

ANDREW SOMMERVILLE, OF PASADENA, CALIFORNIA.

ADJUSTABLE PRICE MARK.

1,413,500.

Specification of Letters Patent. Patented Apr. 18, 1922.

Application filed July 25, 1919. Serial No. 313,316.

To all whom it may concern:

Be it known that I, ANDREW SOMMERVILLE, a citizen of the United States, residing at Pasadena, in the county of Los Angeles 5 and State of California, have invented new and useful Improvements in Adjustable Price Marks, of which the following is a specification.

My object is to make an adjustable price 10 mark, and my invention consists of the novel features herein shown, described and claimed.

Figure 1 is a perspective of a box of fruit with an adjustable price mark embodying 15 the principles of my invention in position for use.

Fig. 2 is an enlarged perspective of the adjustable price mark shown in Fig. 1.

Fig. 3 is a fragmentary perspective detail 20 showing the operation and construction of the price mark.

Fig. 4 is an enlarged fragmentary front elevation of the price mark support.

The stake 1 forms the support for the adjustable price mark and is a straight stick 25 rectangular in cross section and having a sharpened lower end 2. The plate 3, preferably of cardboard or tin, is rectangular in elevation and fits against the front face of 30 the upper end of the stake 1 and is secured in place by tacks 4. The pad 5 of numbers is secured to the front face of one-half of the plate 3.

The pad 5 consists of a series of sheets 6 35 of paper, the sheets being arranged in a pile, each sheet carrying a price number 7, and the numbers being arranged from —0— to —9—. The pile of sheets is secured to the plate 3 by threads or staples 8 inserted 40 through the paper near the edges at one side, so that the sheets may be turned back and forth like a book. In a like manner the pad 9 is applied to the other half of the plate 3. The pads are arranged to open in opposite 45 directions so that the exposed numbers will read together, there being numbers 10 upon the pad 9 corresponding to the numbers 7 upon the pad 5.

The plate 11 of cardboard or tin is secured to the upper edge of the plate 3 by a hinge 12 which may be fabric or tough paper, and the plate 11 has openings 13 and 14 through which the numbers 7 and 10 will

appear when the plate 11 is in its folded position, as in Fig. 2. An opening 15 is 55 formed through the plate 11 in position to be above the numbers 7 and 10, and a strip 16 is provided carrying the title 17.

The strip 16 carrying the title "cherries" 60 is placed against the front face of the plate 3 above the pads 5 and 9, and the plate 11 is folded downwardly against the pads 5 and 9, said pads having been previously 65 opened to disclose the numbers reading —3— and —5—, and the plate 11 holds the pads open to show these numbers through the openings 13 and 14 so that the sign will read "Cherries 35".

If the price advances the plate 11 is raised and the sheet of the pad 5 turned backwardly to disclose the number reading 70 —6—, and if the price lowers the sheet is turned the other way to disclose the number reading —4— and so on.

A finger 18 is placed through an opening 75 19 in the stake 1. A pin 20 is inserted through the stake and through the finger, and a coil spring 21 is placed upon the pin 20, one end engaging the stake and the other end engaging the finger 18, so that when the 80 plate 11 is folded downwardly the finger 18 may be operated to swing out of the way and then released to hold the plate 11 in its folded position.

Various changes may be made without departing from the spirit of my invention as 85 claimed:

I claim:

1. An adjustable price mark comprising a standard, a plate secured to the upper portion thereof, a pad of leaves secured to said plate, said leaves being foldable from one position to another, said leaves bearing indicating characters, a second plate hinged to the upper portion of the first mentioned 90 plate and provided with openings located so as to disclose the indicating characters on the leaves of the pad, and latching means on the standard for engaging the lower edge of the hinged plate to hold it in closed position upon the fixed plate and the pad of 95 leaves thereupon. 100

2. An adjustable price mark comprising a standard, a plate fixed to the upper portion thereof, a pad of leaves secured to said plate 105 and foldable from one position to another,

said leaves bearing indicating characters, a plate hinged to the upper edge of the fixed plate and provided with openings located so as to display the indicating characters on the leaves of the pad, there being an opening formed in the standard adjacent to the lower edges of the fixed and hinged plates,

and a spring actuated catch arranged for operation within said opening and adapted to engage the lower edge of the hinged plate to hold the same in closed position.

In testimony whereof I have signed my name to this specification.

ANDREW SOMMERVILLE
